(57) **CLAIM**

The ornamental design for a hood for a work vehicle, as shown and described.

DESCRIPTION

FIG. 1 is a perspective view of a hood for a work vehicle according to an exemplary embodiment of the present subject matter.

FIG. 2 is a first side view of the hood illustrated in FIG. 1. FIG. 3 is a second side view of the hood illustrated in FIG. 1.

FIG. 4 is a top view of the hood illustrated in FIG. 1.

FIG. 5 is a bottom view of the hood illustrated in FIG. 1.

FIG. 6 is a rear view of the hood illustrated in FIG. 1; and, FIG. 7 is a front view of the hood illustrated in FIG. 1.

The broken lines contained within the figures, including, but, not limited to, any dash-dot broken lines and/or dash-dash broken lines, represent portions of the hood for a work vehicle that form no part of the claimed design. Additionally, contour lines and/or surface shading are illustrated simply for purposes of highlighting the solid-rendering, and, thus, form no part of the claimed design.
